(57) **CLAIM**

The ornamental design for a pendant, as shown and described.

DESCRIPTION

FIG. 1 is a front perspective view of the pendant in an environment related to the use of the claimed design. The broken lines show opposing ends of a necklace chain secured to loops formed at opposite ends of the pendant. The broken lines are provided only for the purpose of illustrating environmental structure related to the claimed design; FIG. 2 is a front plan view thereof; FIG. 3 is a bottom edge view thereof; FIG. 4 is a top edge view thereof; FIG. 5 is a back plan view thereof; FIG. 6 is a left side elevational view thereof; and, FIG. 7 is a right side elevational view thereof.
